US00D871827S

(12) **United States Design Patent** (10) Patent No.: **US D871,827 S**
(45) Date of Patent: ** Jan. 7, 2020

(54) **AIR FRYER HOUSING**

(71) Applicant: **NuWave, LLC**, Libertyville, IL (US)

(72) Inventors: **Jung S. Moon**, Long Grove, IL (US);
Eunjung Huh, Grayslake, IL (US);
Byung G. Choi, Lake Villa, IL (US);
Li Xiang Jun, Foshan (CN); **Zeng Qing Ping**, Shanwei (CN); **Kim Jong Rok**, Seoul (KR); **Huang Zhen Xiong**, Rong Gui Town (CN)

(73) Assignee: **NUWAVE, LLC**, Libertyville, IL (US)

(**) Term: **15 Years**

(21) Appl. No.: **29/673,168**

(22) Filed: **Dec. 12, 2018**

(57) **CLAIM**

The ornamental design for the air fryer housing, as shown and described.

DESCRIPTION

FIG. 1 is a perspective view of a cooking bowl showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

The broken lines shown in the appended figures are for purposes of illustrating environmental structures and form no part of the claimed design.
